United States Patent Office

Des. 221,545

Patented Aug. 24, 1971

221,545

FLOOR TILE OR SIMILAR ARTICLE

John Stanley Madsen, Montgomery Township, Belle Mead County, N.J., assignor to GAF Corporation, New York, N.Y.

Filed June 5, 1970, Ser. No. 33,328

Term of patent 14 years

Int. Cl. D25—01

U.S. Cl. D18—2

Fig. 1.

Fig. 2.

FIG. 1 is a plan view of a floor tile or similar article showing my new design.

FIG. 2 is a cross-sectional view thereof taken on line 2—2 of FIG. 1.

I claim:

The ornamental design for a floor tile or similar article, substantially as shown.
